United States Patent Office

Des. 186,550
Patented Nov. 3, 1959

186,550

ELECTRIC METER

John D. Saint-Amour, Chagrin Falls, Ohio, assignor to
Assembly Products, Inc., Chesterland, Ohio, a corpora-
tion of Ohio

Application April 8, 1958, Serial No. 50,380

Term of patent 14 years

(Cl. D52—1)

FIG. 1

FIG. 2

FIG. 3

Fig. 1 is a perspective view of an electric meter showing my new design;

Fig. 2 is a right end view of the meter, the left end being substantially the same in appearance as the right end, and

Fig. 3 is a rear view of the meter.

I claim:

The ornamental design for an electric meter, as shown and described.
